UNITED STATES PATENT OFFICE.

HENRY PRICE BALL, OF BROOKLYN, NEW YORK, ASSIGNOR TO S. STERNAU & CO., A COPARTNERSHIP COMPOSED OF SIGMUND STERNAU AND LIONEL STRASSBURGER, OF BROOKLYN, NEW YORK.

PORTABLE LAMP FOR BURNING SOLID FUEL.

1,226,625.

Specification of Letters Patent. Patented May 22, 1917.

Application filed January 11, 1916, Serial No. 71,404. Renewed April 4, 1917. Serial No. 159,741.

To all whom it may concern:

Be it known that I, HENRY PRICE BALL, a citizen of the United States, resident of the borough of Brooklyn, county of Kings, city and State of New York, have invented a certain new and useful Portable Lamp for Burning Solid Fuel, of which the following is a specification.

This invention relates to improvements 10 in lamps for use with chafing dishes, coffee machines and other purposes in which a portable lamp is employed.

The objects are:

First: To improve the means of attachment of the cover.

Second: To improve the effect of the lamp when in operation.

These and further objects will more fully appear from the following specification 20 and accompanying drawings, considered together or separately.

In the drawings

Figure 1 is a plan view of a lamp embodying my invention, with the cover removed; and

Fig. 2 is a sectional view on the line 2, 2 of Fig. 1 with the cover in place.

In both views like parts are designated by the same reference characters.

30 Referring to the drawings, the lamp has a body 1. This body is preferably made of sheet metal stamped or otherwise formed to shape. It is adapted to contain a quantity of solid fuel and suitable fuel for this

35 purpose is what is known as solid alcohol. This fuel is adapted to be transported in the body and when in use as a lamp the fuel is ignited, the flame passing out through the open top of the lamp.

40 Around the upper edge of the lamp is a rim 2, preferably made of a separate piece of sheet metal suitably stamped or otherwise formed to shape. This rim is secured to the body in any suitable manner. Below the edge of

45 the rim is an annular recess 3. The inner wall 4 of this recess forms a cover seat. The cover 5 is preferably circular in shape, as shown, having a vertical annular wall adapted to engage with an annular wall 4.

50 The engagement is close so that the cover is secured in place solely by friction. In order to permit the ready removal of the cover it is provided with an annular flange 6 located preferably at a distance from its

lower edge. The cover when applied is introduced within the annular recess the side edge of the cover engaging with the annular wall 4 making a close joint therewith. To remove the cover the latter is raised by pressure applied beneath the flange 6. A suitable tool may be used for this purpose, as desired. Above the vertical wall 4 is a horizontal perforated annular wall 7. The perforations permit entrance of air to assist in supporting combustion of the burning fuel. Inside the wall 7 is a vertical annular wall 8. This is preferably made without perforations. Inside of this latter wall is a second perforated horizontal annular wall 9. These perforations may be smaller than the perforations appearing in the wall 7, but the operation is the same. Inside the annular wall is an annular lip 10 extending upward. This lip acts with a nozzle effect to direct the flame upward. The rim 2 may be easily made by a stamping operation, the perforations being made at the same time. This is a very cheap device to manufacture. I prefer not to put the perforations in the vertical wall 8 for the reason that the perforations in such wall do not admit air so freely as perforations in the horizontal wall, also for the reason that such construction is expensive to make, as the perforations cannot be made with a simple die, as the perforations in the walls 7 and 8 can be made.

The body 1 is shown with a plurality of grooves 11 extending from the bottom of the body to a point below the upper edge thereof. These grooves are shown as merging or tapering into the upper edge of the body. The body is also shown as provided with a circular recess 12. This may be omitted if desired as well as the grooves 11.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. A lamp for use with solid fuel com-

prising a body, a rim thereon with an annular recess inside the edge of the body, a vertical wall inside the recess, there being a series of perforations inside the vertical wall, and a cover surrounding the wall and perforations and lying in the recess.

5. 2. A lamp for use with solid fuel comprising a body, a rim thereon, there being an annular recess in the rim, there being a 10 series of perforations in the rim, and a cover surrounding the perforations and lying within the recess.

15. 3. A lamp for use with solid fuel comprising a body, a rim thereon, there being an annular recess in the rim lying within the body, there being a series of perforations in the rim, and a cover surrounding the perforations and lying within the recess.

20. 4. A lamp for use with solid fuel comprising a body, a rim thereon, there being an annular recess in the rim, there being a series of perforations in the rim, and a cover surrounding the perforations and engaging a wall of the recess.

25. 5. 5. A lamp for use with solid fuel comprising a body, a rim thereon, there being

an annular recess in the rim, lying within the body, there being a series of perforations in the rim, and a cover surrounding the perforations and engaging a wall of 30 the recess.

6. A lamp for use with solid fuel, comprising a body with a rim thereon, an annular recess inside the edge of the body, a vertical wall inside the recess, a plurality 35 of perforated horizontal walls at different elevations, and a cover surrounding the vertical wall and engaging therewith.

7. A lamp for use with solid fuel, comprising a body with a rim thereon, an annular recess inside the edge of the body, a vertical wall inside the recess, a plurality of perforated horizontal walls at different elevations, a centrally located annular lip, 40 and a cover surrounding the vertical wall 45 and engaging therewith.

This specification signed and witnessed this 30th day of December, 1915.

HENRY PRICE BALL.
